United States Patent Office.

E. M. CHUMARD, OF PITTSTON, PENNSYLVANIA.

Letters Patent No. 83,929, dated November 10, 1868.

BRAKE FOR VEHICLES.

The Schedule referred to in these Letters Patent and making part of the same

To all whom it may concern:

Be it known that I, E. M. CHUMARD, of Pittston, in the county of Luzerne, and in the State of Pennsylvania, have invented certain new and useful Improvements in Brakes for Vehicles; and do hereby declare that the following is a full, clear, and exact description thereof, reference being had to the accompanying drawings, and the letters of reference marked thereon.

In the annexed drawing, making a part of this specification, A A represent wheels, and B B represent hounds of a wagon.

C represents a brake-bar, made of suitable length to extend just outside of the wheels A A, and is secured to the hounds B B, as is fully shown.

D represents a metallic rod of suitable dimensions, and just long enough to come out even with the centre of the track of the wheels A A, and is adjusted in suitable bearings alongside of the brake-bar C, and parallel therewith.

The metallic rod D is provided with lugs or ears x x, or has them secured to it in any suitable manner, and has a lever, K, secured to it for the purpose of partially turning or revolving said rod.

I I represent brake-blocks, adjusted between the brake-bar C and the wheels A A, by means of links or loops h h and rods g g.

The links or loops h h pass through the upper end of the brake-blocks I I, and are pivoted or hinged to the bar C on its under side.

The rods g g are pivoted to the lugs x x of the rod D, and to the lower end of the brake-block I, and operate the same backward and forward.

m represents a metallic slotted guide secured to the under side of the bar C, the rod g passing through the slot thereof.

The slotted guide m holds the rod g from lateral strains, and keeps it firmly in its position when working backward and forward.

l represents a spiral spring, adjusted around the rod D for the purpose of throwing it back, and thereby the brake-blocks I I, when the lever K is relieved of the pressure applied to it.

It will readily be seen that the rod D with its lugs x x, being turned by means of the lever K, the brake-blocks I I are thrown back against the wheels A A, by means of the rods g g and links or loops h h. It will also be seen that the top and bottom of said blocks are thrown out so as to wear fairly on their faces, and that when brought back by means of the spring l, they are firmly held against the brake-bar C, so that there will be no rattling or chance of getting loose.

Having thus fully described my invention,

What I claim as new, and desire to secure by Letters Patent, is—

The arrangement of the crank-shaft D, rods g g, arms x x, slotted guides m, loops h h, and brake-blocks I, with the brake-bar C, and operated by the lever K and spring l, all constructed substantially as set forth.

In testimony that I claim the foregoing, I have hereunto set my hand, this 25th day of March, 1868.

E. M. CHUMARD.
